(57) **CLAIM**

The ornamental design for a hearing protection headband as shown and described.

DESCRIPTION

FIG. 1 is a perspective view showing the new design for a hearing protection headband;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

The portions of the hearing protection headband depicted in broken lines in FIGS. 1-8 form no part of the claimed design.
